J. C. McPHAIL,
PLAYER PIANO,
APPLICATION FILED OCT. 25, 1917.

1,277,443.

Patented Sept. 3, 1918.

Inventor,

John C. McPhail;

By *A. B. Leapham*
Attorney

UNITED STATES PATENT OFFICE.

JOHN C. MCPHAIL, OF SOUTH WEYMOUTH, MASSACHUSETTS, ASSIGNOR TO MCPHAIL
PLAYER MANUFACTURING COMPANY, OF BOSTON, MASSACHUSETTS, A CORPORA-
TION OF MASSACHUSETTS.

PLAYER-PIANO.

1,277,443.

Specification of Letters Patent. Patented Sept. 3, 1918.

Application filed October 25, 1917. Serial No. 198,548.

To all whom it may concern:

Be it known that I, JOHN C. MCPHAIL, a citizen of the United States, and a resident of South Weymouth, in the county of Norfolk and Commonwealth of Massachusetts, have invented certain new and useful Improvements in Player-Pianos, of which the following is a full, clear, and exact specification.

10 This invention relates to that type of player pianos in which the action is operated through the agency of air, and it has for its object the construction of improved removable pedals by which the air-pumping bellows are actuated.

15 In the drawings forming part of this specification, Figure 1 is a perspective view of a pair of pedals embodying my improvements. Fig. 2 is a side elevation of the same, 20 the lower front part of a piano with which the same is connected being shown in section. Fig. 3 is a detail view of the two part rod for joining a pedal and the associated bellows, one of the rod-sections being shown 25 in section.

30 Referring to the drawings, the numeral 1 designates a portion of the lower front part of a piano; and 2, one of the two pneumatic actuating bellows. The pedals 3 I prefer to 35 construct from cast metal, hinging them on pivots 4 supported by lugs 5 rising from the base 6, also preferably of cast metal. Either all or parts of this base bar 6 has suitable 40 felt or rubber pads 7 attached thereto in order to protect any hardwood floors upon 45 which the same may be placed.

To keep the base bar 6 in correct relationship with respect to the piano, a slender bar 9 is pivotally secured at one end beneath the 40 bottom frame 1 as shown in Fig. 2, by means of a screw 12, or otherwise, the other end of each bar 9 being bent to form a hook 10 adapted to be engaged with a suitable hole 11 at the corresponding end of the base 45 bar 6.

When the pedals are to be removed from the piano, the bars or rods 9 are disengaged from the base bar 6 and swung around beneath the member 1, practically out of sight.

50 For connecting the pedals with the bellows 2, the rod for uniting each pedal with its bellows is formed in two sections, the section 14 which is joined to the bellows being formed with a socket 15, and the section

16 which connects with the pedal being 55 formed with a finger 17 snugly fitting the socket. The rod section 16 is shouldered about the base of its finger 17 to make the exposed surfaces of the two sections continuous at their juncture. 60

The hole 19 through which each two-part rod 14-16 passes in the member 1 is vertically elongated, as shown in Fig. 1, and the rod itself is somewhat curved, in order to allow for the up and down movement of the 65 pedal end thereof. Each hole is also protected with a thimble 20, both for the sake of neatness in appearance, and for preventing wear of the wood. When the bellows is in its normal collapsed position, the socket 70 end of the rod section 14 is designed to rest substantially flush with the outer surface of the member 1.

75 Since the bellows 2 is always in this type of player pianos provided with a spring for collapsing it, the action of the pedals is always a push and never a pull. Consequently, the two parts of each bar 14-16 will always remain united until such time as the pedals are to be removed, at which occurrence all 80 that requires to be done is to detach the hooked ends of the rods 9 from the bar 6, swing them beneath the piano, and pull the rods 14-16 apart.

85 Although I have shown in Fig. 1, and so described above, that the connecting rods 16 pass through holes 19 in the bottom frame 1, I do not restrict myself to this construction, for the reason that many people may prefer to have their pianos unmarred by 90 holes. For such pianos, I have said rods adapted for going beneath the bottom frame, as illustrated in Fig. 2, the only change being a slightly increased curvature in the connecting rods. 95

What I claim is:

1. The combination with a piano and a player therefor comprising an air-exhausting means, of a pedal having a pivotal support and connections with the air-exhausting 100 means, said connections being longitudinally separable to be disengaged by a pull upon the pedal, whereby an actuating pressure on the pedal is communicated to the air-exhausting means but a pull on the pedal with- 105 draws it from connection therewith.

2. In a player piano having operative bellows, a pedal removably supported having

a two-part rod operatively connecting the pedal and bellows, one of said two parts having a socket, and the other having a finger adapted to be readily introduced into 5 said socket.

3. In a player piano having a hole in its bottom frame and an air exhausting device behind the bottom frame, a base bar removably connected with said bottom frame, a 10 pedal pivoted to said bottom frame, and a two part rod operatively connecting said pedal with said air exhausting device, the part connected with said device having a longitudinally disposed socket, and the other 15 part having a finger adapted to removably enter said socket, said two part rod being movable in said hole.

4. In a player piano having a hole through its bottom frame, and an air exhausting device behind said bottom frame, a base bar 20 detachably connected with said bottom frame, a pedal pivotally supported by said base bar, and a two part rod operatively con-

nected said pedal with said exhausting device, the part connected with said device 25 having a longitudinally disposed socket, and the other part having a finger adapted to removably enter said socket, said two part rod passing through said hole and being adapted to present the juncture of the said parts 30 flush with the outer face of said hole when the exhausting device is in its normal inoperative position.

5. In a player piano having a bottom frame and operative bellows, a pedal detachably connected with said bellows, a base pivotally supporting said pedal and having a hole at each end, and two slender rods pivoted to the under surface of the bottom frame to swing beneath the same, each rod 40 having a hook adapted to be engaged with the hole at its associated end of the bar.

In testimony that I claim the foregoing invention, I have hereunto set my hand this 23rd day of October, 1917.

JOHN C. McPHAIL.
